UNITED STATES PATENT OFFICE.

CHARLES F. SCHRINER, OF CLEVELAND, OHIO.

BUSHING FOR METAL RECEPTACLES.

Application filed October 28, 1925. Serial No. 65,360.

This invention relates to bushings for metallic receptacles, and has for its main object to provide a bushing for ready and quick attachment to the opening of a metal barrel or the like, in such manner that the bushing will be held securely in position against rotation when screwing a bung into or out of said bushing.

Another object of the invention is to provide a bushing of the above character which will not leak.

With the above and other objects in view, the invention will be hereinafter fully described as illustrated in the accompanying drawings, and the distinctive features thereof will be particularly pointed out in the appended claim.

In the drawings, similar characters of reference are used to designate corresponding parts.

Figure 1 is a sectional elevation, on an enlarged scale, of a bushing applied to the end of a metal receptacle in accordance with my invention,

Fig. 2 is a sectional elevation of the end of a metallic receptacle constructed in accordance with my invention, for the application thereto of the bushing, which section is taken on line 2—2 of Fig. 3,

Fig. 3 is a plan view of Fig. 2,

Fig. 4 is a sectional elevation of a bushing constructed in accordance with my invention, and before being applied to the end of the metallic receptacle,

Fig. 5 is a plan view of Fig. 4, and

Fig. 6 is a similar view to Fig. 1 of a modification of the invention.

Referring to the drawings, 1 represents the end of a sheet metal barrel or other receptacle, which is provided with an opening 2 formed by pressing therefrom an inward annular flange 3. Stamped outwardly from the end of the barrel and on the arc of a circle a sufficient distance outside of the opening 2 to leave a seat 4 for a sealing gasket 5, are a plurality of projections 6. A bushing 7 of cylindrical formation having an outside diameter corresponding to the inside diameter of the annular flange 3 for fitting therein and an internally threaded opening 8 for receiving a bung, is provided with a flange 9 having recesses 10 extending from the underside thereof for receiving and fitting over the projections 6 of the end of the barrel. The inner end of the bushing 7 is cut at 11 so as to leave a tapering portion for bending over the inner edge of the annular flange 3 as shown at 12. When the recesses 10 of the flange of the bushing are placed over the projection 6 of the end of the barrel, with a gasket 5 between said end of the barrel and the flange of the bushing, and the inner end of the bushing is bent over the inner edge of the annular flange 3, the bushing is securely fixed in the opening of the end of the barrel and will not be moved or rotated by the action of screwing a bung into the bushing or out of the bushing, and the joint between the bushing and the end of the barrel will be fluid tight.

In Fig. 6 is illustrated a modification of the construction described, in that instead of the recesses 10 in the flange 9, openings 13, extending entirely through the flange 14 of the bushing 15, are provided, which permit the making of the flange 14 of less thickness than the flange 9.

From the drawings and description, it will be seen that such a bushing for metallic barrels or other receptacles is of simple and inexpensive construction, and the same will be held securely in position, and there will be no leakage between the end wall of the barrel and the bushing.

Having fully described my invention what I claim is:

The combination with the wall of a metallic receptacle of a bushing, the wall having an opening formed therein and surrounded by an annular flange, projections formed integrally with and extending from said wall in the opposite direction from said flange, the projections being arranged on the arc of a circle in spaced relation to said opening, the bushing extending through said opening and beyond the end of the annular flange, the bushing having a flange at one end, the flange having recesses extending from the under side thereof and arranged between the bushing and the edge of the flange for receiving and fitting over said projections, a gasket arranged between the wall of the receptacle within the circle formed by said projections and said flange of the bushing, and the other end of the bushing being bent over the end of said annular flange to clamp the bushing in position, substantially as described.

In testimony whereof I affix my signature.
CHARLES F. SCHRINER.
